UNITED STATES PATENT OFFICE.

BERTHOLD HUBER, OF TAUNTON, MASSACHUSETTS.

MECHANICAL MOVEMENT.

No. 892,376.

Specification of Letters Patent.

Patented June 30, 1908.

Continuation of application Serial No. 136,927, filed December 29, 1902. This application filed September 23, 1904.
Serial No. 225,588.

To all whom it may concern:

Be it known that I, BERTHOLD HUBER, a citizen of the United States, residing at Taunton, in the county of Bristol and State 5 of Massachusetts; have invented a new and useful Mechanical Movement, of which the following is a specification.

The object of this invention is to produce a new and improved mechanical movement 10 for converting rotary into reciprocating motion.

The movement has been particularly designed for reciprocating the moving members or beds of printing presses.

15 It is desirable in printing presses to have the reciprocating member or bed move with a uniform speed during the printing action, which movement is accomplished by a mechanism usually termed the "main driving mechanism"; and to provide a crank actuated mechanism for reversing the movement of the bed which is done by slowing down, stopping and starting the bed in the opposite direction. The most desirable 20 reverse is obtained by using a half turn of a crank element such as a wrist-pin. The common way in practice of arranging these instrumentalities has been to use what is known as the "three-revolution arrangement", that is, to arrange the mechanism so 25 that the crank element will make one revolution for the uniform movement of the bed in one direction; a half revolution for the reversal of the bed at one end of its stroke; another revolution for the uniform movement 30 of the bed in the opposite direction; and another half revolution for the reversal of the bed at the end of its stroke in this other direction; or in other words, to make 35 the crank element have the three revolutions for each complete reciprocating movement 40 of the bed. It has been found desirable, however, in the larger sizes of printing presses to give more time to the reversals, as 45 the bed and its parts necessarily are made very heavy and acquire a large momentum when actuated at high speed. To accomplish this, instead of using a three-revolution mechanism, I arrange the parts so that a 50 two-revolution mechanism is provided, and divide the time so that the uniform movement of the bed in one direction will occupy a half revolution of the crank element; the reversal at one end of the stroke will occupy

another half revolution of the crank element; 55 the constant speed movement in the opposite direction will occupy a third half revolution of the crank element; and the reversal of the bed at the opposite end of its stroke will occupy a half revolution of the crank 60 element; or the crank element will make two revolutions for each complete reciprocation of the bed.

By giving a half revolution to the crank element for each reversal of the bed, all the 65 advantages of the full crank reverse are obtained, and a longer and easier reverse is given to the bed as a larger proportion of the total movement is given to the reversing movements as compared with the three revolution arrangement. This desirable result is obtained by making the time of uniform movement equal to the time of the reversing movement, or in other words, dividing the 70 time of operation into four aliquot parts between the uniform speed movements and the reversing movements, a uniform speed movement, of course, occurring alternately with a reversing movement. As the crank element necessary with the time relation before 75 described is making the same half turn for both reversing movements of a complete cycle, and as the reversing movements must be in opposite directions if a single crank element is used, it is necessary to provide a direct and 80 change motion connection between the crank element and the bed for opposite reversals, and this is a distinctive feature of my invention. Further, as the time relation before 85 described is particularly advantageous in 90 large printing presses, and as it is particularly desirable to make such printing presses set low, I provide in combination with the two-revolution crank element a main driving mechanism which is geared to turn faster 95 than the crank element, whereby it may be reduced in size and the bed kept low down.

The invention further consists of certain details hereinafter particularly pointed out in the claims at the end of this specification. 100

In the accompanying two sheets of drawings, I have shown the invention as adapted to a drum-cylinder printing-press, although, of course, it may be adapted to any form of printing press in which a reciprocating bed is 105 employed and any arrangement of impression cylinder or cylinders used in connection with said bed.

In the drawings, Figure 1 is a side elevation of enough of a printing press to illustrate the operation of my invention. Fig. 2 is a sectional elevation taken on the line 2—2 of Fig. 3. Fig. 3 is a sectional plan view taken on the line 3—3 of Fig. 2. Figs. 4 to 6 inclusive are diagrams illustrating the reversal at the forward end of the machine which I term the "direct reversal", and Figs. 7 to 9 inclusive are similar diagrams illustrating the reversal at the rear end of the machine which I term the "change motion reversal".

Referring to the drawings and in detail, A 15 designates the frame work, and B the bed which is mounted to reciprocate on the frame-work in the usual way, and which carries the printing form or forms F. C designates the impression cylinder. These parts 20 are arranged in the ordinary way, and require no further description.

Attached to the bed in different vertical planes are an upper rack 10 and a lower rack 11. These racks are alternately engaged by 25 a driving pinion 12 which is mounted on a sliding shaft 13, which shaft carries a pinion 14 meshing with a crank gear D to which power is applied in any of the ways common in printing presses.

The crank-gear D is mounted on a shaft 30 15, arranged on which is a pinion 16 which meshes with a gear 17 of double the size thereof mounted on a shaft 18, arranged on which is a cam 19. A lever 20 is arranged on 35 the end of a shaft which is journaled vertically in a bracket carried by the framing, and said lever has a roller engaging the groove of said cam 19, and a roller at its other end engaging a grooved collar 21 on the driving 40 shaft 13.

The mechanism before described constitutes in substance a main driving mechanism which is geared to turn faster than the crank-gear D, and hence is reduced in size, whereby 45 the mechanism may be arranged in small compass vertically.

The gear 14 is usually made one-half the size of the driving gear D, whereby the driving gear 12 will make one complete turn for 50 each uniform speed movement of the bed, the racks 10 and 11 being made of a length substantially equal to a pitch circumference of said driving gear 12. The driving gear 12 is shifted by the cam 19 so as alternately to 55 engage said racks 10 and 11.

A gear 22 is arranged on the shaft of the impression cylinder C, and is geared with the gear 17. The gear 22 on the impression cylinder is made twice the diameter of the 60 crank gear D so that the impression cylinder will turn once for each two revolutions of the crank-gear, which is the proper speed for a drum-cylinder machine.

Mounted on the crank-gear D is a crank 65 element or wrist-pin 27 which carries a

block 26 which engages a slot 25 in a horizontally reciprocating yoke or slider E which is arranged in guide-ways 24 and 23 outside the frame-work A. The wrist-pin 27 is set on said crank-gear D so that its radius will substantially equal the pitch diameter of the driving gear 12. Arranged on said yoke or slider E is a rack 28 which engages a pinion 29 mounted on a shaft 30 which carries a pinion or reversing gear 31 the same size as 70 the pinion 29 at its inner end. Short reversing racks 32 and 33 are arranged on the bed, and are oppositely disposed relatively to the reversing pinion 31 so as to get a direct and change motion reverse.

Referring now to the diagrams:—suppose that the crank gear D has just made such a half revolution, or the driving gear 12 such full revolution as to have caused the bed to have made its return or retrograde uniform speed movement relatively to the impression cylinder. This will bring the parts to the position shown in Fig. 4 where said driving gear 12 is just running out of mesh of the lower rack 11, and where the oscillating reversing pinion 31 is just engaging the lower reversing rack 33. Now during the next quarter revolution of the crank element 27 the yoke or slider E will be moved to the right at a speed commencing at the constant 85 speed movement of the bed and gradually diminishing to zero. This motion by means of rack 28, pinion 29, shaft 30, reversing pinion 31, and reversing rack 33 will be directly imparted to the bed at the same speed 90 and in the same direction. This will bring the parts to the position shown in Fig. 5. During the next quarter revolution of the crank element 27 the yoke E will be moved to the left at a speed commencing from zero 100 and gradually accelerating up to the uniform speed movement of the bed, and this motion will be directly imparted to the bed by the connections before described. During the time of the last described half revolution of 105 the crank-element the driving gear 12 will have been shifted axially so that it will now engage the upper rack 10. This will bring the parts to the position shown in Fig. 6.

Thus it will be seen that the crank element, 110 the yoke and the connections to the reversing rack 33 constitute a reversing mechanism which will give a full crank half-turn reverse to the bed in a direct manner, or in the same direction as the yoke itself is moved. During the next half turn of the crank element 115 the driving gear 12 will make one revolution in mesh with the upper rack 10, which will impart the uniform speed motion to the bed on its forward stroke to the left as shown in the diagrams. This will bring the parts to the position shown in Fig. 7. Now during the next quarter revolution of the crank-element the yoke or slider E will be moved to the right at a speed commencing at 120

125

the diagrams. This will bring the parts to the position shown in Fig. 7. Now during the next quarter revolution of the crank-element the yoke or slider E will be moved to the right at a speed commencing at 130

the uniform speed movement of the bed and gradually decreasing to zero, and this motion will be imparted to the reversing pinion 31. But during this action the reversing pinion 31 will be in mesh with the reversing rack 32 which is oppositely disposed to the shaft of said pinion 31 relatively to the rack 28 on the yoke E, whereby the motion now imparted to the bed will be in the reverse direction from that in which the reciprocating yoke E is moving, whereby, although the slowing down motion obtained by the crank element will be imparted to the bed it will be in an opposite direction relatively to the before described direct reverse between Figs. 4 and 5. This change motion reverse will bring the parts to the position shown in Fig. 8. Now during the next quarter revolution of the crank-element, the yoke or slider E will be moved to the left at a speed gradually accelerating from zero up to the uniform movement of the bed, and by the change motion connection before described this movement will be imparted to the bed but in a reverse direction relatively to that in which the yoke is moving. Thus it will be seen that the reversing mechanism when acting through the rack 32 will constitute a change-motion reversing mechanism. By this arrangement the motion of the bed will be reversed and the two-revolution cycle will be completed.

The movement of the bed under the uniform speed will thus be a half circumference of the crank element, or a pitch circumference of the driving pinion, and each reversing movement will occur in a travel back and forth equal to the radius of said crank element, or a pitch diameter of the driving pinion, and the total stroke will be a half circumference of the crank element plus a diameter thereof, or a pitch circumference of the driving pinion plus two pitch circumferences thereof. In the specific illustration each alternate part of the cycle takes one complete revolution of the driving gear.

It will be seen that the reversing actions at each end of the bed take place as the crank element makes its right-hand revolution relatively to a vertical line, looking at the diagrams, and that the direct and change motion connections before described allow for the same movement of the crank-pin to accomplish the opposite reversals. By this arrangement, therefore, a two-revolution driving mechanism is arranged which still keeps the ideal reversing properties of the half-turn crank reverse.

I am aware that it has heretofore been proposed to use a two-revolution driving pinion for actuating the beds of printing presses as shown in patent to Robert Miehle, No. 317,663, dated May 12, 1885; but to do this, the use of two wrist-pins was necessary, which in the particular mechanism shown in this pat-

ent, necessarily lead to the sacrifice of the full half-turn or true crank reverse, and to the accomplishment of a reverse which only occupies thirty or forty degrees of the revolution of the crank element instead of one-hundred and eighty degrees or a full half-turn which is necessary to accomplish the desirable results heretofore pointed out. In contra-distinction to this mechanism, I believe I am the first to obtain a full half-turn or true crank reverse with a two-revolution crank-element, and by so doing, I am enabled to give heavy, large printing press beds a much longer and smoother reverse than has heretofore been possible, whereby I am enabled to increase materially the speed of this class of machinery.

While the invention as herein described is shown or applied to actuate the reciprocating bed of a printing press, of course, it may be applied to other mechanisms.

The details and arrangements herein described may be greatly varied by a skilled mechanic without departing from the scope of my invention as expressed in the claims.

Having thus fully described my invention, what I claim and desire to secure by Letters Patent is:—

1. In a mechanical movement, the combination of a reciprocating member, a main driving mechanism for imparting a movement thereto at a uniform speed, and a reversing mechanism for slowing down stopping and starting the member in the opposite direction, the time of the uniform speed movement being equal to the time of the reversing movement.

2. In a mechanical movement, the combination of a reciprocating member, a main driving mechanism for imparting forward and back movements thereto at a uniform speed, and a reversing mechanism for slowing down stopping and starting the member in the opposite direction at each end of its stroke, the time of operation being divided into four aliquot parts between the uniform speed movements and the reversing movements.

3. In a mechanical movement, the combination of a reciprocating member, a shaft making two revolutions for each complete reciprocation thereof, a main driving mechanism for imparting movements to the member at a uniform speed, and a reversing mechanism, the main driving mechanism acting alternately with the reversing mechanism, and each action taking a half revolution of said shaft.

4. In a mechanical movement, the combination of a reciprocating member, a main driving mechanism for imparting the uniform speed movements thereto, a single crank-element making two revolutions for each complete reciprocation of the member, and means for connecting said crank element

- to the member for the reversal movements having a direct and change-motion connection as between opposite reversals.
5. In a mechanical movement, the combination of a reciprocating member, a main driving mechanism for imparting uniform speed movements thereto, a single crank-element making two revolutions for each complete reciprocation of the member, a reversing member reciprocated by said crank-element, and means for connecting said reversing member to said reciprocating member for the reversing movements thereof, said connections comprising a direct connection for the reversal at one end and a change motion connection for the reversal at the other end.
6. In a mechanical movement, the combination of a reciprocating member, a main driving mechanism for imparting uniform speed movements thereto, a single crank-element making two revolutions for each complete reciprocation of the member, a reversing member actuated by said crank element, a gear oscillated by said reversing member, and reversing racks carried by said bed and oppositely disposed relatively to said oscillating gear to provide for a direct and change-motion reversal from said crank-element.
7. In a mechanical movement, the combination of a reciprocating member, a main driving mechanism for imparting uniform speed movements thereto, a crank-actuated slider carrying a rack, a pinion engaging said rack, a reversing gear actuated by said pinion, and two reversing racks carried by the reciprocating member, said reversing racks being arranged to engage said reversing pinion on opposite sides of its axis.
8. In a mechanical movement, the combination of a reciprocating bed, a revolving shaft making two revolutions for each complete reciprocation of the bed, a main driving mechanism geared to turn faster than said shaft, whereby it is reduced in size, and a reversing mechanism actuated by said shaft.
9. In a mechanical movement, the combination of a reciprocating bed, a revolving shaft actuating a crank element and making two revolutions for each complete reciprocation of the bed, a reduced main driving mechanism geared to said shaft, and direct and change-motion connections from said crank-element to said bed for accomplishing the reversals thereof.
10. In a mechanical movement, the combination of a reciprocating member, a main driving mechanism for giving the same its uniform movements, a crank-actuated reversing mechanism for giving the same its reversing movements at each end of its travel, the uniform movement constituting a travel equal to one-half the pitch circumference of the crank, and each reversal occurring in a travel equal to the radius of the crank.
11. In a mechanical movement, the combination of a reciprocating member, a crank-element, a main driving mechanism having a driving pinion geared to the crank-element to make twice as many revolutions, and a reversing mechanism actuated by said crank-element, the arrangement being such that each uniform movement will take one complete revolution of the driving pinion, and so that each reversing movement will also occur during one complete revolution of the driving pinion.
12. In a mechanical movement, the combination of a reciprocating member, a crank-element, a main driving mechanism having a driving pinion geared to the crank-element to make twice as many revolutions, and a reversing mechanism, whereby the member will move a circumference of the driving pinion on its uniform movements and a diameter thereof back and forth on its reversing movements.
13. In a mechanical movement, the combination of a reciprocating member, a rack and pinion driving mechanism for imparting a movement thereto at a uniform speed, and a reversing mechanism for slowing-down, stopping and starting the member in the opposite direction; the time of the uniform speed movement being equal to the time of the reversing movement.
14. In a mechanical movement, the combination of a reciprocating member, a rack and pinion driving mechanism for imparting a movement thereto at a uniform speed, a continuously rotating wrist-pin, and a reversing mechanism for slowing-down, stopping and starting the member in the opposite direction; the time of the uniform speed movement being equal to the time of the reversing movement.
15. In a printing press, the combination of a frame-work, a bed mounted to reciprocate thereon, a main driving mechanism arranged inside of the frame-work for imparting the uniform speed movements to the bed, a crank actuated reversing member arranged to reciprocate outside of the frame-work, and means for connecting the same to the bed for the reversing movements.
16. In a printing press, the combination of a frame-work, a bed mounted to reciprocate thereon, a main driving mechanism arranged inside of the frame-work for imparting the uniform speed movements to the bed, a slider arranged outside of the frame-work, a crank for reciprocating the same, and gearing extending from said slider to the inside of the frame-work for connecting the slider to the bed for the reversing movements.
17. In a mechanical movement, the combination of a frame-work, a bed mounted to reciprocate thereon, a main driving mechanism arranged inside of the frame-work for imparting the uniform speed movements to

the bed, a slider mounted to reciprocate outside of the frame-work, a crank for reciprocating the slider, a rack carried by the slider, a pinion engaging said rack, a shaft extending inside of the frame-work, a reversing pinion arranged on said shaft, and reversing racks carried by the bed.

In testimony whereof I have hereunto set my hand, in the presence of two subscribing witnesses.
